HOLDER

Charles W. Sievert, Los Angeles, Calif.

Application August 8, 1949, Serial No. 4,348

Term of patent 3½ years

(CL. D85—2)

To all whom it may concern:

Be it known that I, Charles W. Sievert, a citizen of the United States, residing in the city and county of Los Angeles and State of California, have invented a new, original, and ornamental Design for a Combination Ash Tray and Flower Holder, of which the following is a specification, reference being had to the accompanying drawing, forming part thereof.

Fig. 1 is a perspective view of a combination ash tray and flower holder, showing my new design.

Fig. 2 is a top plan view.

Fig. 3 is an exploded view in side elevation.

I claim:

The ornamental design for a combination ash tray and flower holder, substantially as shown.
CHARLES W. SIEVERT.
